UNITED STATES PATENT OFFICE.

OLLIE BEDELL, OF ELMORE, MINNESOTA.

DESIGN FOR A BREAST-PUMP.

SPECIFICATION forming part of Design No. 29,475, dated October 11, 1898.

Application filed July 16, 1898. Serial No. 686,180. Term of patent 7 years.

To all whom it may concern:

Be it known that I, OLLIE BEDELL, a citizen of the United States, residing at Elmore, in the county of Faribault and State of Minnesota, have invented and produced a new and original Design for Breast-Pumps, of which the following is a specification, reference being had to the accompanying drawing, forming part thereof.

10 In the drawing is represented a side elevation of my new design for a breast-pump.

As shown in the drawing, the leading and material feature of the design consists of a trumpet-shaped vessel A, having a hollow U-shaped vessel B formed on its side. At the 15 apex of the trumpet-shaped vessel A is formed an annular groove C, and at its outer end is

formed an outwardly-flaring flange D. The walls of the U-shaped vessel B extend from the trumpet-shaped vessel A substantially 20 parallel to a vertical line drawn from the longitudinal axis of the vessel A and connect to the walls of the trumpet-shaped vessel with a slight curve.

Having described my invention, what I 25 claim, and desire to secure by Letters Patent, is—

The design for a breast-pump as herein shown and described.

OLLIE BEDELL.
